E. J. BRANDT.
CALCULATING IMPLEMENT.
APPLICATION FILED MAR. 24, 1906.

941,004.

Patented Nov. 23, 1909.

UNITED STATES PATENT OFFICE.

EDWARD J. BRANDT, OF WATERTOWN, WISCONSIN, ASSIGNOR TO BRANDT CASHIER COMPANY, OF CHICAGO, ILLINOIS, A CORPORATION OF ILLINOIS.

CALCULATING IMPLEMENT.

941,004.

Specification of Letters Patent. Patented Nov. 23, 1909.

Application filed March 24, 1906. Serial No. 307,787.

To all whom it may concern:

Be it known that I, EDWARD J. BRANDT, a citizen of the United States, and resident of Watertown, in the county of Jefferson 5 and State of Wisconsin, have invented certain new and useful Improvements in Calculating Implements; and I do hereby declare that the following is a full, clear, and exact description thereof.

10 Referring to my previous applications Serial No. 259,130, filed May 6, 1905, renewed January 29, 1908, Serial No. 413,268, and Serial No. 307,788, filed March 24, 1906, my invention consists in certain peculiarities of 15 construction and combination of parts herein shown; described and claimed as constituting a simple, economical, and durable portable implement for the convenience of a seller by which to calculate money value of 20 sales and indicate the same to a cashier, who may or may not employ the implement in conjunction with a suitable machine, such as is disclosed in the aforesaid applications, to make a record, registration or both of 25 what is from time to time indicated by said implement.

My invention also consists in making the implement with receptacles, in order that it may also serve as a sales-ticket holder and 30 cash-carrier.

Figure 1 of the drawings represents a horizontal section view of an implement in accordance with my invention organized for all of the several purposes above stated, Fig. 35 2, a front elevation of the same as it would appear suspended from a traveler, and Fig. 3, a transverse section view of said implement.

Referring by letter to the drawings, A indicates a tablet having a face thereof provided with a series of longitudinal grooves in which slides B have their play and the tablet is shown as provided with a back compartment b in which to place sales-tickets. 40 45 It is also preferable to attach a receptacle C to the back of the tablet to therewith form a pocket for cash, one end of said receptacle being preferably extended beyond an edge of said tablet and provided with ears c with 50 which to attach a hanger.

Each slide B is provided with a finger-notch d to facilitate its adjustment, and the several slides are transversely kerfed at regular intervals longitudinally thereof to pro-

vide indentations for the engagement of 55 catch-fingers e of a spring-plate D riveted or otherwise fastened to the tablet, and an arm f of this spring-plate opposes a thumb-extension g of a latch-plate E in pivotal connection with said tablet and normally engaged with kerfs of all the slides, it requiring a tilt of the latch-plate, against resistance of said arm of the spring-plate, in order that any one or all of said slides may be adjusted out of normal position or back 60 to the same. The catch-fingers e of the spring-plate are such that each of them engages a kerf in a corresponding slide to hold 65 said slide in any position of adjustment when the latch-plate is tilted out of kerfs of 70 all the several slides, there being ready yield of said catch-fingers to adjustment of the respective slides.

It is preferable, as herein shown to mark the spaces between kerfs of each slide with 75 the Arabic numerals in ascending order beginning with the cipher, and the slides themselves are in the order of units, tens, hundreds etc., reading from right to left when the tablet aforesaid is held with the notches 80 d of said slides toward the operator. All of the slides are of the same length and when in normal position they all project an equal distance from one end of the tablet 85 in which they are adjustable. The tablet, slides and other devices in connection therewith constitute a portable implement by which to calculate and indicate money values.

An adjustment of one or more of the slides out of normal position is made to designate the total money value of a sale. For instance twelve dollars and twelve cents is 90 designated by the adjustment of the units, tens, hundreds and thousands slides to the positions shown in Fig. 2, each adjusted 95 slide being as many steps or spaces out of normal position as corresponds to the numeral thereon or space thereof next back of the forward cross-piece h of the spring-plate D bounding a slot in the same. The 100 adjustment of the proper slide or slides having been effected by a seller, the implement as a whole is ready for transportation to a cashier, with or without a sales-ticket (single, duplicate, triplicate or otherwise) as 105 well as with or without cash with which to pay the money value indicated, no footing on said sales-ticket being necessary, be-

cause of the same having been designated by the adjustment of a slide or slides as aforesaid.

The implement may be suspended on a traveler for transportation from the seller to the cashier and return, and it is to be understood that the ticket and cash receptacles of said implement are only preferable adjuncts to other parts of the same required for calculating and indicating total money value of sales from time to time.

The adjusted slides of the implement may be employed in engagement with a machine similar to what is set forth in the applications aforesaid to effect a corresponding adjustment of recording slides or the operation of register-mechanism or both.

I claim:—

1. A portable calculating implement comprising a tablet provided with longitudinal guideways, a series of slides transversely indented at intervals longitudinally thereof and independently adjustable in the guideways beyond an end of the tablet to indicate arbitrary designations, and a plate in rigid connection with said tablet having spring-fingers each automatically engageable with indentations of a slide to hold the same extended at various adjustments thereof beyond said end of the aforesaid tablet.

2. A portable calculating implement comprising a tablet provided with longitudinal guideways open at one end, a series of slides transversely indented at intervals longitudinally thereof and independently adjustable in the guideways beyond the open ends of same to indicate arbitrary designations, and a single latch-plate in pivotal spring-controlled connection with the tablet for engagement with indentations of all the slides regardless of their adjustment.

3. A portable calculating implement com-

prising a tablet, slides in adjustable connection with the tablet to indicate arbitrary designations, a spring-plate fastened to said tablet and having fingers engaging the slides to stop the same in various adjustments thereof, and a latch-plate for said slides in pivotal connection with the aforesaid tablet and having a thumb-extension opposed to an arm of the spring-plate.

4. A portable calculating implement comprising a tablet provided with a sales-ticket back compartment, adjustable computing slides for designating the total money value of a sale, guideways for the slides, and means for holding each slide extended in adjusted position beyond an end of its guideway.

5. A portable calculating implement comprising a tablet provided with a back-receptacle and adjustable computing slides, said receptacle constituting a pocket for cash with which to pay the money value of a sale as designated by an adjustment of one or more of said slides out of normal position beyond an end of the tablet.

6. A portable calculating implement comprising a tablet provided with a sales-ticket compartment, adjustable computing slides for designating total money value of a sale, and a pocket for cash with which to pay said money value of the sale designated by an adjustment of one or more of said slides out of normal position beyond an end of the tablet.

In testimony that I claim the foregoing I have hereunto set my hand at Chicago in the county of Cook and State of Illinois in the presence of two witnesses.

EDWARD J. BRANDT.
